DESIGN FOR A STROLLER

Nellie B. Spence, Springfield, Mo.

Application October 26, 1945, Serial No. 123,225

Term of patent 14 years

(Cl. D14—14)

To all whom it may concern:

Be it known that I, Nellie B. Spence, a citizen of the United States, residing at Springfield, in the county of Greene and State of Missouri, have invented a new, original, and ornamental Design for a Stroller, of which the following is a specification, reference being had to the accompanying drawings, forming part thereof.

and

I claim:

The ornamental design for a stroller as shown.

NELLIE B. SPENCE.
